(57) **CLAIM**

The ornamental design for a drying unit for cleaning appliance, as shown and described.

DESCRIPTION

1. Drying unit for cleaning appliance

2. Drying unit for cleaning appliance

1.1 : Front

1.2 : Back

1.3 : Left

1.4 : Right

1.5 : Top

1.6 : Bottom

1.7 : Perspective

1.8 : Perspective

1.9 : Perspective

1.10 : Enlarged

1.11 : Enlarged

2.1 : Front

2.2 : Back

2.3 : Left

2.4 : Right

2.5 : Top

2.6 : Bottom

2.7 : Perspective

2.8 : Perspective

2.9 : Perspective

2.10 : Enlarged

2.11 : Enlarged

1.1 to 1.6 are six orthographic projection views of a first drying unit for cleaning appliance showing our new design;

(Continued)

1.7 to 1.9 are three perspective views thereof; 1.10 and 1.11 are two enlarged views of “part A” and “part B” circled in 1.7, respectively; 2.1 to 2.6 are six orthographic projection views of a second drying unit for cleaning appliance showing our new design; 2.7 to 2.9 are three perspective views thereof; 2.10 and 2.11 are two enlarged views of another “part A” and “part B” circled in 2.7, respectively.
